UNITED STATES PATENT OFFICE.

LOUIS BERNSTEIN, OF CHICAGO, ILLINOIS.

SLEEVE CUFF.

Application filed July 23, 1925. Serial No. 45,474.

My invention relates to sleeve cuffs, designed especially for use on infants' garments, to take the place of mittens or the like and to close up the open wrist ends of the sleeves whereby effectively to protect the hands and arms of the wearer from cold or inclement weather, and my invention has for its main object the provision of an improved article of this character which will embody the desired features of simplicity, convenience, ornamentation, and which will be economic in manufacture.

Other objects will appear hereinafter.

The invention consists in the combinations and arrangements of parts hereinafter described and claimed.

The invention will be best understood by reference to the accompanying drawings, forming a part of this specification, and in which,

Fig. 1 represents a front view of an infant's garment provided with a form of my sleeve closure cuffs;

Fig. 2 is a fragmental view of a sleeve of the kind illustrated in Fig. 1, but showing the back thereof;

Fig. 3 represents a front view of the garment illustrated in Fig. 1, but showing the sleeve closure cuffs in the position they occupy when not in use for closing the open wrist ends of the sleeves;

Fig. 4 is a fragmental view of a sleeve like that illustrated in Fig. 3, but looking at the back thereof;

Fig. 5 represents an enlarged fragmental view, showing the cuff as it appears when the end of the sleeve is open and with the flaps flaring;

Fig. 6 is a sectional view taken on the line 6—6 of Fig. 5;

Fig. 7 represents a view similar to that shown in Fig. 5, but illustrating the cuff as it appears when closing the end of the sleeve and with the flaps flaring;

Fig. 8 is a sectional view taken on the line 8—8 of Fig. 7;

Fig. 9 represents the back of a sleeve, fractionally shown and illustrating a modified form of cuff;

Fig. 10 represents a front view of the sleeve and means thereon for securing this modified form of the cuff;

Figs. 11 and 12 are back and front views, respectively, of the sleeve, showing the modified form of cuff as it appears when closing the open wrist end of the sleeve;

Figs. 13 and 14 are front and back views, respectively, of fragmental sleeves showing a still further modified form of my improved cuff, the view depicted in Fig. 13 showing the cuff applied to the sleeve but not closing the open wrist end thereof, while the view depicted in Fig. 14 shows the cuff as closing the open wrist end of the sleeve; and

Fig. 15 is an enlarged detail view of the form of cuff shown in Figs. 13 and 14.

The accompanying drawings illustrate the preferred embodiment of my invention; one such embodiment being illustrated in detail in Figs. 1 to 8, in which the reference characters 17 and 16 represent the front and back members of my improved cuff, the back member 16 having an extension 18 secured under an ornamental band 19 that surrounds the front and back members 20 and 21 comprising the garment sleeve. The said ornamental band 19 may itself be a fixed cuff of any usual type attached to the sleeve adjacent the open wrist end thereof; and it will be observed in this connection that the extension 18 on the back member 16 of the cuff is secured under the ornamental band 19 at the back 21 of the sleeve.

The form of my improved cuff under discussion, has at the opposite ends of said front and back members 17 and 16 projecting flap parts 23, which are sewed, seamed or otherwise suitably secured together along their front and rear sides 24 and 25 and at their ends 26. The front and back members 17 and 16 are also secured together in similar manner along their rear sides or edges 27; but they are open at 28 along their front sides or edges in order to provide an entrance-way into the interior or pocket 29 of the cuff. The cuff thus composed of the front and back members 16 and 17 with their connected end flaps 23 is adapted to be

swung as upon a hinge along a line 30 at the rear edge of the ornamental band 19. When the cuff is in open position, that is, when the open wrist end of the sleeve is uncovered, as best illustrated in Figs. 3 to 6, the back member 16 may be secured to the front member 17 near the opening 28 by means of button 31 and a button-hole 32, the button being attached to the back member 16 while the button-hole is provided in the front member 17. When the cuff is in this open position the flaps 23 thereof may be secured one over the other upon a button 33 attached to the front 20 of the sleeve, the said flaps 23 for this purpose being provided with suitable button-holes 34. In this manner, the cuff may have its front and back parts firmly secured together, and may as a whole fit the sleeve over the wrist or hand of the wearer.

When the cuff is to be used as a closure for the open wrist end of the sleeve, the flaps 23 are disconnected from the button 33 and the front member 17 is disconnected from the button 31; and thereupon the cuff is swung over the fingers and the open wrist end of the sleeve is entered in the pocket 29 of the cuff as best illustrated in Figs. 1, 2, 7 and 8. When the cuff thus encompasses the end of the sleeve, the button-hole 32 in the front member 17 is applied to a button 35 secured to the front 20 of the sleeve. When the cuff is thus placed in closed position over the open wrist end of the sleeve the end flaps 23 are secured one upon the other upon a button 36 attached for the purpose to the back member 16. In Fig. 1, this form of cuff is shown as applied to the sleeves of an infant's garment 37 and in closed position thereon, the flaps on the cuff at the left-hand side of the figure being shown as closed while the flaps at the right-hand side of the figure are indicated in broken lines as being open. In Fig. 3 the cuffs are shown as being secured upon the sleeves in the positions they occupy when turned back to leave the open wrist ends of the sleeves free and unobstructed.

In Figs. 9 to 12, inclusive, I depict a modified form of cuff 38 which is secured, as in the previous instance, upon the back 39 of the sleeve to swing or turn thereon along the rear edge 40 of the ornamental band 41. This form of sleeve closing cuff is made substantially like the form above described, except that the end flaps are omitted and that the front member 42 is provided along its free edge 43 with spaced button-holes 44 adapted, when the open end of the sleeve is inserted in the cuff, as illustrated in Figs. 11 and 12, to be engaged upon suitable correspondingly spaced buttons 45 secured upon the front 46 of the sleeve. When the cuff is in open position, as illustrated in Fig. 9, it is secured to the back 39 of the sleeve,

there being a button-hole 47 provided along the edge 47' of the cuff for securement upon a button 48 attached to the said back 39.

In Figs. 13 to 15, inclusive, I illustrate a preferred detachable form of sleeve closing cuff. In this detachable form of cuff I employ two corresponding members comprising, for the purposes of identification, a front member 49 and a back member 50, the same being secured together all around except at their sides 51 which are left free and open in order that the cuff may be engaged over the open end of the sleeve. The members 49 and 50 are provided with corresponding button-holes 52 so as to be secured, when the sleeve is not to be closed, upon suitable buttons as 53 attached to the back 54 of the sleeve. When the open end of the sleeve is to be closed with this form of cuff, the button-holes 52 of the back 50 are engaged upon the buttons 53 of the sleeve back 54, while the button-holes in the front member 49 are engaged over suitable buttons 55 attached to the front 56 of the sleeve.

From the foregoing description, taken in connection with the accompanying drawings, it will be observed that I have provided a very simple, practical and effective sleeve closing cuff; one that may be economically manufactured either with or without the end flaps; and one that is especially adapted for use in connection with the sleeves of infants' garments, although, obviously, it may be also used to advantage in connection with the garments of adults.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. In combination, a garment sleeve; a cuff having sleeve encircling parts; means for securing the cuff upon the sleeve; a member associated with the cuff and forming an openable pocket therewith for receiving the open end of the sleeve therewithin; means for securing said member to the sleeve in sleeve closing position; and means for connecting said sleeve encircling parts, substantially as described.

2. A garment sleeve having an open wrist end; a cuff arranged on the sleeve and composed of parts adapted to encircle the sleeve and openable to slip over said open wrist end and entirely enclosing the same; and flaps projecting from opposite ends of the cuff and forming therewith an encircling

band, said flaps being adapted to be secured one upon the other, substantially as described.

3. A garment sleeve having an open wrist end; a cuff arranged on the sleeve and composed of sleeve encircling parts forming a closure for receiving the open wrist end wholly therewithin; and flaps on the cuff adapted to form therewith an encircling

band around the sleeve and to be secured to the sleeve when the cuff is not in sleeve closing position and to be secured to the cuff when the last mentioned is in sleeve closing position, substantially as described.

In testimony whereof I have signed my name to this specification.

LOUIS BERNSTEIN.
